STEAM COOKING POT

Donald Gordon Cheyne, 47A 12th St., Parktown North,
Johannesburg, Transvaal, Republic of South Africa

Filed Jan. 24, 1972, Ser. No. 220,539

Claims priority, application Republic of South Africa
July 22, 1971

Term of patent 14 years

Int. Cl. D7—02

U.S. Cl. D7—85

FIG. 1 is a side elevational view of a steam cooking pot showing my new design;

FIG. 2 is a top perspective view thereof; and

FIG. 3 is a top plan view thereof on an enlarged scale. The bottom of the steam cooking pot, not shown, is plain and unornamented.

I claim:

The ornamental design for a steam cooking pot, as shown and described.
